US00D978092S

(12) **United States Design Patent** (10) **Patent No.:** **US D978,092 S**
Altonen et al. (45) **Date of Patent:** ** *Feb. 14, 2023

(54) **CONTROL DEVICE**(71) Applicant: **Lutron Technology Company LLC**,
Coopersburg, PA (US)(72) Inventors: **Gregory Altonen**, Easton, PA (US);
Chris Dimberg, Easton, PA (US);
Jason C. Killo, Emmaus, PA (US)(73) Assignee: **Lutron Technology Company LLC**,
Coopersburg, PA (US)

(*) Notice: This patent is subject to a terminal disclaimer.

(**) Term: **15 Years**(21) Appl. No.: **29/809,651**(22) Filed: **Sep. 29, 2021****Related U.S. Application Data**

(63) Continuation of application No. 29/709,557, filed on Oct. 15, 2019, now Pat. No. Des. 933,615.

Primary Examiner — Selina Sikder(74) *Attorney, Agent, or Firm* — Saidman DesignLaw
Group, LLC(57) **CLAIM**

The ornamental design for a control device, as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines illustrate structure or features which form no part of the claimed design.
